UNITED STATES PATENT OFFICE.

JESSE G. ROSEBOOM, OF CINCINNATI, OHIO.

ILLUMINATING SIGNAL.

Application filed October 22, 1923. Serial No. 670,168.

To all whom it may concern:

Be it known that I, JESSE G. ROSEBOOM, a citizen of the United States, residing at Cincinnati, in the county of Hamilton and 5 State of Ohio, have invented new and useful Improvements in Illuminating Signals, of which the following is a specification.

My present invention pertains to illuminating means for direction signals such as are 10 used on motor vehicles, and it contemplates the provision of a series of reflectors so constructed and arranged that the direction signal will at the proper time be clearly illuminated in order to enable a person to 15 readily and easily determine the contemplated direction of travel of the vehicle as well as the intention of the operator as to the action he will cause said vehicle to take.

Other objects and characteristic features 20 will be fully understood from the following description and claims when the same are read in connection with the drawings accompanying and forming part of this specification in which:

25 Figure 1 is a view partly in section and partly in side elevation of a direction signal and my novel illuminating means secured thereto.

Figure 2 is a side elevation of a portion of 30 the reflectors of the device and the sockets to which said reflectors are secured.

Figure 3 is an end elevation of one reflector, signal box, supporting bracket and one gear operating the box.

35 Figure 4 is a fragmentary view of the reflector, support and the illuminating means.

Figure 5 is a detail view of one of the 40 sockets for the illuminating bulb and showing a modified construction of the socket.

Figure 6 is a detail view of one supporting bracket.

Figure 7 illustrates the elements of one socket as disassembled.

Figure 8 is a side and end view of the connecting device for adjoining reflectors.

Figure 9 is a detail view of one of the reflectors.

Similar numerals of reference designate 50 corresponding parts in all the views of the drawings.

My novel device is illustrated as supported on a stationary bracket 1 having the upstanding end portions 2; and adapted to act as a bearing in the aperture of the ends 55 is a collar or flange 3. The bracket 1 may be secured in any appropriate manner on a

motor vehicle for convenient manipulation of the operating mechanism of the operator.

An electric bulb is provided on the socket from which extends the wiring 5 and at its 60 end opposite the bulb the socket is provided with threaded portion 4 that engages a threaded nut or collar 4^a that is made secure to and forms a part of the supports 2; said supports being too narrow to receive a 65 thread.

The collar 4^a is similar to element 3 and is inserted in an opening in the support 2 as shown in Fig. 5.

Secured to the end of the socket so as to 70 prevent interference in removal of the bulb, is a reflector 9 preferably of cone shape in cross-section that is provided with a threaded end as illustrated to engage a cap 10 having a flange to confine the lens 11. The collar 4^a is used to mount the wheel 14 on the stem of the lamp. 75

To the cap 10 I secure a reflector 12 which is slightly more than semi-circular in cross-section and is pitched at an angle as illustrated with respect to the lens 11 whereby the rays from the bulb will strike the reflector 12 and reflect its rays at an angle so that a perforated or transparent sign placed in front of the reflector 12 will be illuminated. 80 Obviously such illumination is superior to that produced by placing a bulb only and not a bulb and reflector in rear of the transparent sign. 85

When two bulbs are used in one sign, one 90 at each end, there is a space between the two reflectors 12—12 Figure 1, which permits connection of the reflectors to the lens.

These reflectors are secured to each other by means of the spring clip 15 having the 95 bent end portions 15^a.

Using the sockets 3 inserted in supports 2, as shafts, I mount a movable revolving signal box 13 having end walls.

I have not illustrated transparent material on the side walls of the box but I prefer that same be employed. 100

The signal box comprises frames 13 and a toothed gear 14 is secured on one end of the frame and rotation of the frames may be accomplished by means of the gear 14 in connection with any form of actuating gears. Manifestly transparent sides are to be formed in the frame with direction signals produced in said sides. 105

By reference to the drawings it will be seen that I provide one end of the socket 110

with a stud 8 that enters the bayonet slot 7 of the member 6.

In practice the box is revolved to the position desired and this moving of the box will not disturb the stationary position of the illuminating means. However, the rays will at all times be thrown on the reflectors 12 and hence be directed through the transparent material.

Having described my invention, what I claim and desire to secure by Letters-Patent is:—

1. A signal comprising, in combination, two spaced vertical supports, a lamp socket secured in each support, lamps carried by the sockets and directed toward each other, a casing having transparent walls bearing legends and enclosing the lamps, the sockets of the lamps being journaled in the end walls, a semicylindrical reflector attached to each lamp, the ends of the reflectors being in contact with each other and secured to

each other, and means to rotate the casing about the reflector.

2. In a signal, the combination of spaced vertical supports, lamp sockets mounted in the supports and having their open ends directed toward each other, a casing mounted on the supports and enclosing the sockets; said casings having transparent walls bearing legends, the sockets being journaled in the end walls of the casing, a semi-cylindrical reflector attached to the sockets and being secured to each other at their meeting end and manually operated means for rotating the reflector about the sockets.

In testimony whereof I have hereunto set my hand in presence of two subscribing witnesses.

JESSE G. ROSEBOOM.
